AUTOMOTIVE SPOTLIGHT

Raymond T. Larson, Park Ridge, Ill., assignor,
by mesne assignments, to Arnolt Corporation,
a corporation of Indiana

Application September 5, 1946, Serial No. 694,963

6 Claims. (Cl. 240—61.13)

1

This invention relates to automotive spotlights and particularly to such spotlights that embody a universal mounting for the light and means for operating the light from the interior of the automobile.

Automotive spotlights of the general character to which the present invention relates have in the past been arranged for universal movement or adjustment by operating means disposed within the body of the automobile, but such prior spotlights have been relatively complicated in structure so as to be expensive to manufacture and difficult to assemble, and to enable these objectionable characteristics to be eliminated in spotlights of the aforesaid character is the primary object of the present invention. An object related to the foregoing is to simplify the motion transmitting means in such spotlights whereby the universal adjusting movement is transmitted from the operating handle to the spotlight. More specifically it is an object of the present invention to enable adjusting movement of the light about one of the mounting axes thereof to be transmitted from the operating handle by means of a flexible character such as a cable so as to thereby simplify the manufacture as well as the assembly and adjustment of the spotlight.

Other and further objects of the present invention will be apparent from the following description and claims and are illustrated in the accompanying drawings which, by way of illustration, show a preferred embodiment and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings,

Fig. 1 is a fragmentary side elevational view of a spotlight embodying the features of the invention;

Fig. 2 is a plan view taken partly in section and illustrating the manner in which the spotlight is mounted;

Fig. 3 is a longitudinal vertical sectional view of the spotlight construction;

Fig. 3A is a perspective view of the lamp supporting stud;

Fig. 4 is a longitudinal view taken along the line 4—4 of Fig. 3;

Fig. 5 is a vertical sectional view taken along the line 5—5 of Fig. 3;

2

Fig. 6 is a sectional view generally similar to Fig. 5 and taken along the line 6—6 of Fig. 3;

Fig. 7 is a view similar to a portion of Fig. 4 and illustrating the operating mechanism in one extreme position of adjustment; and

Fig. 8 is a view similar to Fig. 7 and showing the parts in the other extreme position of adjustment.

For purposes of disclosure the invention is herein illustrated as embodied in a spotlight 10 that is shown in its operative or mounted position on an element of an automobile body such as the front column 11 that borders one edge of the windshield 12 of the automobile body. The column 11 in which the spotlight 10 is supported is normally selected as being the one located adjacent to the driver's seat in the automobile body, and the spotlight 10 is so related to the column 11 that a supporting torque tube 15 of the spotlight extends through the column so as to support a universally mounted lamp 16 outside of the vehicle body while an operating handle 17 is supported on the inner end of the operating tube 15 and within the automobile body so as to be readily accessible to the operator.

The operating tube 15, as shown in Figs. 1 and 2 of the drawings, is extended through suitable openings 19 and 20 formed in the column 11, and on the outer face of the column 11 a mounting fixture 22 is secured to the forward or outer face of the column 11 by means such as screws 23 that are shown in Figs. 1 and 3 of the drawings. The fixture 22 has an internally threaded neck 22N formed thereon and into which a cup-shaped retainer 24 is threaded as indicated at 24A in Fig. 3. The retainer 24 has an internal bore 24B that is arranged to snugly embrace and afford a rotative bearing for the mounting tube 15, and the mounting tube extends forwardly or outwardly of the bore 24B and extends into the stem 26S of a mounting head 26; the stem 26S having a bore 26B formed therein which engages the mounting tube 15 with a drive or frictional fit such that rotation of the tube 15 will impart rotative movement to the fitting 26 about the axis of the tube 15. The right-hand end of the stem 26S, as viewed in Fig. 3, has a reduced portion 26R that is extended into the cup-shaped member 24; and a pin 27 extended through the cup-shaped member 24 is engaged with a groove 24G formed in the reduced portion 26R so as to thereby hold the stem 26S and the mounting tube 15 against withdrawal in a left-hand direction with respect to the cup-shaped member 24. It will be observed that the face 22F of the mounting member 22 engages the outer surface of the column 11, and to enable the face

45

45

50

55

22F to be properly located in abutment with the face of the column, the axis of the neck 22N is disposed at what may be termed an acute angle to the plane of the face 22F. After the fitting 22 has been put in position, the stem 15 may be inserted in a right-hand direction as viewed in Fig. 3 so as to thereby bring the screw-threaded portion 24A into position so that it may be screwed into the threaded neck 22N.

After the operating tube 15 has been thus put into position, a retaining hub 29 which is of a split-collar construction is put into position on the tube 15 and in abutment with the inner face of the column 11, and a clamping screw 30 in the hub 29 is tightened so that the hub 29 engages the tube 15 with a firm frictional action. The relationship of the hub 29 however is such that the tube 15 may be rotated therein, even when the screw 30 is tightened, and an arm 29A extended downwardly from the collar 29 is secured to the column 11 by means such as a screw 31 so as to hold the collar 29 against rotation. The collar 29 is arranged to cooperate with a thrust collar 32 that is clamped by means of a screw 33 in a predetermined longitudinal and rotative relation on the tube 15, and interengaging teeth 32T and 29T enable the collars 29 and 32 to cooperate to limit rotative movement of the tube 15. The tension applied to the stationary hub 29 by tightening of the screw 30 is such that the tube 15 will be held frictionally in any position of rotative adjustment to which it may be moved.

The handle 17 is secured on the rear or inner end of the tube 15 and this is accomplished by affording a split-collar construction 17C, Figs. 1 and 3, whereby the handle 17 may be clamped upon the inner end of the tube 15. Thus as will be evident in Figs. 3 to 5, the handle 17 has a bore 17B formed therein into which the inner end of the tube 15 may extend, and by tightening a clamping screw 35, the handle 17 may be secured in any desired longitudinal and rotative adjustment on and with respect to the tube 15.

The mounting fitting 26 is utilized to support the lamp 16 and to this end, the mounting fitting 26 has an upwardly extending portion 26U that is bored at right angles to the bore 26B as indicated at 26M, the bores 26B and 26M being arranged to intersect. The upwardly extending portion 26U is utilized to afford a rotatable bearing upon which the lamp 16 may be rotated on an axis that is perpendicular to the axis of the bore 26B, and for this purpose a fitting 16F secured to the body of the lamp has an annular seat 16S that rides upon the upper end of the extension 26U, there being an annular flange 16M on the fitting 16F that extends downwardly into a seat afforded by a rabbeded annular groove or counterbore 26R that is formed in the bore 26M. A mounting stud 40 is extended upwardly as viewed in Fig. 3 through an opening 41 formed in the fitting 26 coaxially with respect to the bore 26M, and the head 40H of the stud 40 is disposed within a counterbore 41C so as to bear against an expansive spring 42 that is disposed within the counterbore 41C. At its upper end, the mounting stud 40 has a reduced squared portion 40R that extends upwardly through a complementary opening in the fitting 16F and is secured thereto by means including a clamping screw 44. The stud 40 thus serves to hold the fitting 16F in position on the seat 26R, and by rotation of the stud 40, rotation may be imparted to the lamp 16 about the axis of the annular seat

26R. In the course of such rotation, a continuous electrical connection to the light bulb of the lamp 16 is afforded by means including a wire 47 extended from the light bulb of the lamp, a wire 48 extended through the tube 15 from the handle 17, and a rotatable electrical connection 50 that is afforded between the fitting 26 and 16F, as shown in Fig. 3 of the drawings.

The desired rotative movements are under the present invention imparted to the mounting stud 40 by flexible cable means that are extended from the mounting stud 40 through the mounting tube 15 for association with operating means forming a part of the handle 17. Thus as will be evident in Figs. 3 to 8, an elongated flexible operating cable 55 is secured to and wound about the mounting stud 40 and the opposite end portions 55R and 55L are extended inwardly from opposite sides of the stud 40 and through the mounting tube 15 and the bore 17B of the handle, and within the handle these ends of the operating cable 55 are associated with an operating stud 56 that is arranged for rotation by a laterally projecting cylindrical portion 17H of the handle 17. In fixing the cable 55 to the stud 40, a transverse slot 40S is extended downwardly in the stud 40, as shown in Figs. 3A and 4, to substantially the level of the axis of the bore 26B. The cable 55 is then inserted into the slot 40S and 30 to the bottom of such slot, and is then wound about the stud as shown in Figs. 3, 3A, and 4, so that the ends 55L and 55R extend from opposite sides of the stud and through the tube 15. Such connection of the cable with the stud 35 40 is of course effected before the stud 40 is secured in position in the fitting 26.

The rotatable stud 56 to which the inner ends of the cable 55 are connected is relatively long and is extended downwardly through the handle

40 17 so as to have the upper end thereof disposed within a bore 57 formed in the handle 17, and a separately formed head 56H of the stud 56 is disposed within a counterbore 57C of the bore 57. A spring 58 is disposed within the counterbore 57C so as to act against the head 56H, and the head 56H is drawn downwardly so as to compress the spring in a manner that will hereinafter be described in detail. The bore 57 is arranged as shown in Figs. 3 to 6, so as to enter 50 into an enlarged transverse bore formed in the handle 17 so as to afford a chamber 59, and the lower end of the chamber 59 is closed by a separately formed bottom plate member 60 which has a sleeve portion 60S formed thereon which extends upwardly into the chamber 59 so as to afford a rotative bearing for the stud 56 at a point that is spaced considerably in a downward direction from the bearing afforded by the bore 57. Below the lower flat face of the bottom 60 enclosure member 60, the shaft or stud 56 is formed, as will be evident in Figs. 3, 5 and 6, so as to afford a square portion 56S, and this square portion 56S of the stud 56 is engaged by a complementary opening 62 formed in the upper wall 65 of the handle element 17H, there being a washer 63 having a squared opening 63S formed therein and disposed between the upper end of the handle portion 17H and the lower face of the bottom plate 60. The lower end of 70 the handle section 17H is afforded by a separate member 65 that is flanged at 66 so as to cooperate and laterally interlock with the lower end of the handle portion 17H, and a screw 67 is extended upwardly through the section 65 and is threaded at 68 into the lower end of the squared

portion of the stud 56. Thus when the screw 67 is tightened, the stud 56 is drawn downwardly against the tension of the spring 58, and hence the stud is held in position and a frictional action is introduced between the washer 63 and the plate 60 tending to maintain the stud 56 in any rotative position to which it may be adjusted by the operator. At substantially the level of the axis of the bore 17B, stud 56 has a transverse bore 69 formed therein, and a longitudinal bore 70 in the stud 56 is extended downwardly from the bore 69 so as to open into a transverse slot 71 formed in one face of the square portion 56S of the stud 56 at such a point as to be disposed within the handle section 17H. The bore 70 extends throughout the length of the stud 56, and tapped portions at the opposite ends of this bore are utilized to receive the bolt 67 and the threaded anchoring stem of the head 56H. The bores 69 and 70 are utilized in providing proper connection between the ends of the cable 55 and the stud 56. Thus after being wound about the stud 56 at the level of the bore 69, the end 55R of the cable is extended into the right hand end of the bore 69 as viewed in Fig. 6 and then is extended downwardly through the bore 70 and into the slot 71. Similarly the left hand end of the cable 55L is wound about the stud 56 and is extended into the left hand end of the bore 69 and then downwardly through the bore 70 and into the slot 71. The ends of the cable 55 are then anchored within the slot 71 by means of a clamping plate 77 and a clamping screw 78. When the cable 55 is thus being associated with the stud 56, the screw 67 is removed and the stud 56 is projected upwardly so that the opening or bore 69 is accessible above the handle 17. After the cable has been properly wound about the stud 56 and the ends of the cable have been passed downwardly through the bore 70 and into the slot 71, the stud 56 may be moved downwardly into the position shown in Fig. 3 and after drawing the cable relatively tight the clamping screw 78 may be tightened to secure the ends of the cable 55 to the stud 56. The handle 17H may then be put in position so as to complete the assembly, and the cable portions between the two studs 40 and 56 may be finally tensioned by moving the handle 17 in an inward direction until the desired tension is reached, and by tightening of the screw 35, the handle 17 may be secured in this position. It will be observed in this regard that the handle 17 is preferably disposed in such a position that the stud 56 is parallel to the stud 40.

In the spotlight of the present invention means are afforded on the handle 17 for controlling the operation of the lamp 16 and such switch means are shown in Figs. 3 and 4 of the drawings. Thus the chamber 59 has a rearward extension 80 formed therein so as to extend downwardly to the bottom of the handle section 17, and the lower end of this chamber 80 is enclosed by a portion 60P of the plate 60. Within the chamber 80, a pair of aligned slots 82 are formed in the opposite walls of the chamber so as to extend to the lower end of such chamber, and spaced outwardly from the slots 82, another pair of similar slots 84 are formed. The slots 82 serve as a mounting means for an insulating plate 85, and a terminal 87 is provided on the plate 85 to which the inner end of the wire 48 is connected. Another terminal 89 is also provided on the plate 85 and a wire 90 is connected to the terminal 89

and is extended outwardly through the handle 17 so that it may be connected to a source of electrical power. The slots 84 serve as a mounting for a switch plate 92 that has a switch handle 93 formed thereon so as to project through a slot 94 formed in the inner face of the handle 17. The switch plate 90 is somewhat shorter in a vertical sense than the slots 84 so that the switch member or plate 92 may be moved up and down in the slots 84. On the inner face of the switch plate 92, a spring contact member 96 is mounted, and when the switch plate 92 is in its upper position this contact 96 engages the two stationary contacts 87 and 89 to thereby complete a circuit from the wire 90 to the wire 48, and when this is done the lamp of the spotlight is energized. It will be evident of course that when the bottom plate 60 is removed, the insulating plate 85 may be moved downwardly into such a relation that the wire 48 may readily be connected thereto, and thus the electrical connections may readily be completed at the time when the spotlight is being installed.

From the foregoing description it will be evident that the spotlight that is afforded by the present invention is unusually simple in construction and is so arranged that it may readily be mounted in its position of use upon an automobile body. It will also be evident that the provision of flexible cable means for imparting rotative movement to the light about one of its axes of adjustment renders the present spotlight unusually economical insofar as cost of manufacture may be concerned, and this feature of construction also materially simplifies assembly and adjustment of the spotlight on an automobile. The present invention also affords an unusually simple switch arrangement that is adapted for convenient connection to the lead wire that extends from the light, and the arrangement is such that this electrical connection may be established readily and easily at the time when the operating cable is being adjusted and fixed in position.

Thus while I have illustrated and described the preferred embodiment of my invention, it is to be understood that this is capable of variation and modification and I therefore do not wish to be limited to the precise details set forth, but desire to avail myself of such changes and alterations as fall within the purview of the following claims.

I claim:

1. In a universal spotlight, an elongated cylindrical mounting tube, means fixed at one end of said tube and affording a bearing, a lamp secured on said bearing for rotation on an axis perpendicular to the axis of said tube, a flexible cable operatively connected to said lamp for imparting rotation to said lamp and extended through said tube, a handle base secured to the other end of said tube and having a transverse chamber formed therein and a longitudinal bore establishing communication between said tube and said transverse chamber, a stud having a central bore formed therethrough and having a cylindrical outer surface adjacent one end and a non-circular outer surface throughout at least a portion of the balance of its length, means forming part of said base and disposed at one end of said chamber to afford a first bearing for rotatably supporting said stud, a removably associated end wall for said chamber affording a second bearing for said stud, means at said one end of said stud for limiting movement of the stud in one direction relative to said base, a hollow handle element surrounding and fixed to the other end of said stud in a rota-

tively inter-locked relation to said non-circular surface of said stud and acting against said end wall to hold said end wall in position and limit endwise movement of said stud in the other direction relative to said base, said stud having a transverse opening intersecting said longitudinal bore, and said cable being extended into said transverse opening and said longitudinal bore of said stud and into said hollow handle, and means disposed in said hollow handle and adjustably fixing said cable to said stud.

2. In a universal spotlight, an elongated cylindrical mounting tube, means fixed at one end of said tube and affording a bearing, a lamp secured on said bearing for rotation on an axis perpendicular to the axis of said tube, a flexible cable operatively connected to said lamp for imparting rotation to said lamp and extended through said tube, a handle base secured to the other end of said tube and having a transverse chamber formed therein and a longitudinal bore establishing communication between said tube and said transverse chamber, a stud having a central bore formed therethrough and having a cylindrical outer surface adjacent one end and a non-circular outer surface throughout at least a portion of the balance of its length, means affording spaced bearings for rotatably supporting said stud, a removably associated end wall for said chamber, a washer disposed against the outer surface of said wall, means including a spring at said one end of said stud for limiting movement of the stud in one direction relative to said base, a hollow handle element surrounding and fixed to the other end of said stud in a rotatively inter-locked relation to said non-circular surface of said stud and acting against said washer to hold said end wall in position and limit endwise movement of said stud in the other direction relative to said base, said spring being operable to impart a frictional action between said washer and said base to retard rotative movement of said handle, said stud having a transverse opening intersecting said longitudinal bore, and said cable being extended into said transverse opening and said longitudinal bore of said stud and into said hollow handle, and means disposed in said hollow handle and fixing said cable to said stud.

3. In a universal spotlight, an elongated cylindrical mounting tube, means fixed at one end of said tube and affording a bearing, a lamp secured on said bearing for rotation on an axis perpendicular to the axis of said tube, a flexible cable operatively connected to said lamp for imparting rotation to said lamp and extended through said tube, a handle base secured to the other end of said tube and having a transverse chamber formed therein and a longitudinal bore establishing communication between said tube and said transverse chamber, a stud having a central bore formed therethrough and having a cylindrical outer surface adjacent one end and a non-circular outer surface throughout at least a portion of the balance of its length, means forming part of said base and disposed at one end of said chamber to afford a first bearing for rotatably supporting said stud, a removably associated end wall for said chamber affording a second bearing for said stud, switch means mounted in said handle and including a terminal plate removably disposed in said handle and held in position therein by said end wall, means at said one end of said stud for limiting movement of the stud in one direction relative to said base, a hollow handle element surrounding and fixed to the other end of said

stud in a rotatively inter-locked relation to said non-circular surface of said stud and acting against said end wall to hold said end wall in position and limit endwise movement of said stud in the other direction relative to said base, said stud having a transverse opening intersecting said longitudinal bore, and said cable being extended into said transverse opening and said longitudinal bore of said stud and into said hollow handle, and means disposed in said hollow handle and fixing said cable to said stud.

4. In a universal spotlight, an elongated tube, a lamp mounted on said tube adjacent to one end thereof for rotation about a first axis perpendicular to the axis of said tube, means for mounting said tube for rotation about its axis to thereby afford the other of the axes of adjustment for said lamp, a handle base mounted on the other end of said tube and having a chamber formed therein and opening laterally through one side of said base and having an elongated slot opening through the end of said base, a terminal plate removably disposed in said chamber and having spaced terminals thereon, a switch plate slidably mounted in said chamber having a contact thereon movable into bridging engagement with said terminals by sliding movement of said switch plate, an operating element on said switch plate and extended through said slot, a closure member for said lateral opening and operable to hold said terminal plate in position in said chamber, a handle element, means releasably securing said handle element on said handle base for rotation about an axis perpendicular to the axis and operable to hold said closure member in an effective closing relation to said lateral opening of said handle base, and flexible cable means extended through said tube and operatively connected to said handle element and said lamp to transmit rotative movement of said handle element to said lamp.

5. In a universal spotlight, an elongated tube, a lamp mounted on said tube adjacent to one end thereof for rotation about a first axis perpendicular to the axis of said tube, means for mounting said tube for rotation about its axis to thereby afford the other of the axes of adjustment for said lamp, a handle base detachably mounted on the other end of said tube and having a chamber formed therein and opening laterally through one side of said base and having an elongated slot opening from said chamber through the end of said base, said chamber having two spaced pairs of guide grooves formed in the sides thereof parallel to said slot, a closure member for lateral opening, a terminal plate disposed in one of said pairs of grooves and having spaced terminals thereon, a switch plate slidably in said other pair of grooves and having a contact thereon movable into bridging engagement with said terminals by sliding movement of said switch plate, an operating element on said switch plate and extended through said slot, a handle element, means releasably securing said handle element on said handle base for rotation about an axis perpendicular to the axis and in position to hold said closure member in an effective closing relation to said lateral opening of said handle base, and flexible cable means extended through said tube and operatively connected to said handle element and said lamp to transmit rotative movement of said handle element to said lamp.

6. In a universal spotlight, an elongated tube, a lamp mounted on said tube adjacent to one end

thereof for rotation about a first axis perpendicular to the axis of said tube, means for mounting said tube for rotation about its axis to thereby afford the other of the axes of adjustment for said lamp, a handle base detachably secured on the other end of said tube and having a chamber formed therein and opening laterally through one side of said base and having an elongated slot opening through the end of said base, said chamber having two pairs of guide grooves formed in the sides thereof parallel to said slot, a closure member for lateral opening, a terminal plate disposed in one of said pairs of grooves and having spaced terminals thereon, a switch plate slidable in said other pair of grooves and having a contact thereon movable into bridging engagement with said terminals by sliding movement of said switch plate, an operating element on said switch plate and extended through said slot, a handle element, means including a stud extended 15 through said handle base and releasably securing

10

5

said handle element on said handle base for rotation about an axis perpendicular to the axis and operable to hold said closure member in an effective closing relation to said lateral opening of said handle base, and flexible cable means extended through said tube and operatively connected to said handle element and said lamp to transmit rotative movement of said handle element to said lamp.
